(57) **CLAIM**

We claim the ornamental design for an axle carrier for a model vehicle, as shown and described.

DESCRIPTION

FIG. 1 is a right elevation view of an axle carrier for a model vehicle;

FIG. 2 is a left elevation view thereof;

FIG. 3 is a rear elevation view thereof;

FIG. 4 is a front side elevation view thereof;

FIG. 5 is a top plan view thereof;

FIG. 6 is a bottom plan view thereof;

FIG. 7 is a top, front, left perspective view thereof;

FIG. 8 is a top, front, left perspective environmental view thereof; and,

Figure 9 is an enlarged detail top, front, left environmental view thereof, taken from the lower right section of FIG. 8. Structural elements depicted by broken lines have been shown for the purpose of illustrating portions of the axle carrier for a model vehicle and its environment that form no part of the claimed design.
